CLAIM

The ornamental design for an outdoor storage tent, as shown and described.

DESCRIPTION

FIG. 1 is a front perspective view of the present invention; FIG. 2 is a rear isometric view thereof;

FIG. 3 is a front view thereof;

FIG. 4 is a rear view thereof;

FIG. 5 is a right-side view thereof;

FIG. 6 is a left-side view thereof; and,

FIG. 7 is a top plan view in elevation of the invention of FIG. 1.

The broken lines shown on FIGS. 1 and 3 represent lines of stitching and form part of the claimed design.
